UNITED STATES PATENT OFFICE.

JOSEPH A. MACLENNAN, OF PHILADELPHIA, PENNSYLVANIA, ASSIGNOR TO LINK-BELT COMPANY, OF CHICAGO, ILLINOIS, A CORPORATION OF ILLINOIS.

CONVEYER.

1,300,438.

Specification of Letters Patent. Patented Apr. 15, 1919.

Application filed April 28, 1917. Serial No. 165,058.

To all whom it may concern:

Be it known that I, JOSEPH A. MACLENNAN, a citizen of the United States, residing at Philadelphia, in the county of Philadelphia and State of Pennsylvania, have invented a certain new and useful Improvement in Conveyers, of which the following is a specification.

My invention relates to improvements in conveyers and has for one object to provide means for conveying material downwardly from an elevated source of supply and depositing it more or less generally beneath such source of supply whereby material will not be broken or unduly comminuted and whereby the receptacle such as a vessel or barge will be filled gradually and evenly without damage to the vessel or to the material and without undue dirt, dust and noise. One object of my invention is to provide such a downwardly acting conveyer and operate it in unison with adjustable means whereby there may be at all times a direct line of movement and line of material moving from the elevated source to the relatively low discharge point. Other objects will appear from time to time in the specification.

My invention is illustrated more or less diagrammatically in the accompanying drawings wherein—

Figure 1 is a section through a boat showing the apparatus in elevation;

Fig. 2 is a detailed section through the conveyer leg which penetrates the boat;

Fig. 3 is a side elevation of a detail viewed from the back side of the part shown in Fig. 2;

Fig. 4 is a section on an enlarged scale showing a detail.

Like parts are indicated by like characters in all the drawings.

A is a boat or barge having an open loading hatchway A¹. It stands alongside a wharf or dock A³ upon which is erected a loading trestle A⁴ carrying a return railroad track A⁵ and a dumping track A⁶. A⁷ is a movable crane platform mounted on wheels A⁸ and adapted to travel along the crane track A⁹ there being a space within the tracks for the passage of a railroad car not here illustrated.

Projecting upwardly from the platform A⁷ is a tower B and projecting outwardly from the platform is a boom B¹. This boom

is free to rotate being supported at its outer end from the tower B by means of a tackle B² controlled from inside the housing covering the platform by any suitable mechanism not here shown. B³ is a tubular elevator leg suspended by means of the tackle B⁴ from the end of the boom B¹ the tackle terminating in a drum on the housing not here specifically illustrated whereby the leg may be raised and lowered at the will of the operator.

C is a discharge chute or hopper located beneath the dumping tracks A⁶. It discharges into a fixed leg C¹ the discharge being controlled by a door C² which may be rotated to time or control the flow of material in any suitable way by means of a belt C³ driven by any suitable power not here shown. The leg C¹ is open on its outboard side as at C⁴. The opening extends from substantially the top of the leg well down toward the bottom. The leg or column is adapted to be closed at the bottom of the opening by means of a traveling discharge head C⁵ which fits within the column and is provided with an inclined deflecting bottom C⁶. Carried on this head are a series of plates C⁷ C⁸ which plates are arranged so as to be suspended one from another so that when the head is at the bottom position the opening in the side wall of the column above the discharge head is closed and that as the head is raised successive plates are raised by it. This arrangement permits the head to raise and lower and to maintain at all times a continuous solid column of material in the hollow leg. It will be understood that this head and these shutter sections are raised and lowered by means of a cable C⁹ driven from a motor C¹⁰. This motor also operates cable C¹¹ C¹² which assists in raising and lowering the chute C¹² through which the material is discharged.

D D¹ are sprocket wheels mounted inside the leg B³. A sprocket chain travels over them carrying a series of conveyer buckets D² D². These conveyer buckets are adapted to rotate in a clockwise direction, and to discharge their load on the inclined adjustable chute D³ whence the material passes out through the opening D⁴ in the lower end of the leg into the hollow in the vessel. D⁵ is a gear mounted on the same shaft as the sprocket D¹. It is in mesh with a pinion D⁶ on a shaft D⁷; the shaft D⁷ extends out-

wardly through the wall of the leg and has mounted thereon a gear D⁸. This gear is in mesh with a pinion D⁹ driven from any suitable source of power to control and drive the buckets though it will be understood, of course, that this power source may be dispensed with if the weight of the material is sufficiently great to overcome friction and cause the buckets to descend by gravity.

- 10 It will be noted that one side of the leg B³ is open as at E. E¹ is a carriage adapted to travel in such opening. This carriage is suspended by means of a hoisting line E² leading to a drum in the controlling platform whereby this carriage may be moved with respect to the leg so that the leg and carriage may assume any position between the position of full line and dotted line at the will of the operator. E³ is a measuring 15 and material supply device. It is mounted for rotation as indicated inside the carriage E¹ and is adapted when in the position of full line to discharge its contents into the successive buckets, the gap between the edge 20 of the measure and the buckets being bridged by a short bridging member E⁴. This measuring member carries a gate E⁵ which cuts off the flow of material from the chute C¹² when it is in the full line position. 25 When in the dotted line position the measuring member is filled by material coming down the chute and on the next movement the load is discharged into the bucket. E⁶ is a driving link pivoted at one end on the 30 measuring device E⁵, at the other end on a crank wheel E⁷ in the carriage E¹.

F is a sprocket chain riding over the crank wheel sprocket E⁷ guided by means of sprockets F¹ F¹ and extending about 35 sprockets F² F³ at the bottom and top of the leg respectively. The sprocket F³ is mounted on the shaft F⁴ which shaft carries a sprocket F⁶ about which travels a sprocket chain F⁶ in mesh with a sprocket wheel F⁷ on the shaft D⁷, the relations of these 40 different sprockets, shafts and chains being such that as the buckets travel the measuring and feeding device operates so as to discharge a load in each bucket as the bucket 45 passes by. In other words while one bucket is coming down to take the place of the preceding one which has just been filled, the supply device has time to make one full excursion so that it returns and meets the next 50 bucket and discharges its load into it as it comes by.

It will be evident that while I have shown in my drawings an operative device, still many changes might be made both in size, 55 shape and arrangement of parts without departing materially from the spirit of my invention and I wish therefore that my drawings be regarded as in a sense diagrammatic.

I have shown my device mounted on a 60 bracket or carriage whereby it may be

moved along the chain of buckets. Obviously, of course, it might be equally desirable to move the chain of buckets and hold the carriage in fixed position or it might be desirable to swing the boom which supports the conveyer and in any of these different cases it will be understood that the device will continue this operation in the usual manner without changing in arrangement or function or operation. 75

The use and operation of my apparatus are as follows:-

Ordinarily my apparatus will be when inoperative held with the movable leg in raised position with the movable chute in raised 80 position and with the carriage projecting into the gap between the chute and the leg in position with respect to the leg shown in dotted lines. The hollow leg fixed on the wharf will also be in the position shown in 85 Fig. 1.

When it is desired to load a vessel the movable leg will be lowered until it reaches the bottom of the hold. If the vessel is deep or the water low it will be necessary to lower 90 the movable chute as well and the shutter sections across the front open side of the fixed leg will be successively suspended each from the one above it until the movable leg reaches the bottom of the vessel. As this is 95 done it will be understood that coal which is first in the fixed chute on the loading dock will run down into the fixed leg so that the leg will be filled up as rapidly as its bottom sinks. This, of course, will be accomplished 100 by starting the means of controlling the flow from the hopper as soon as the movable chute is lowered. The operator will then start the movement of the buckets in the movable leg and this will cause the operation of the feeding 105 device in the carriage attached to the movable leg. The result will be that there will be a continuous stream of coal running through the system from the hopper filled by the cars through the first feed gate in the 110 fixed hollow leg down through it into the top of the inclined movable chute, down through this chute into the feed device in the carriage and associated with the movable leg and from this feed device into the successive 115 buckets in the movable leg. These buckets will travel down carrying the material to the bottom of the leg where it will be dumped on the inclined chute and there by it distributed in the bottom of the vessel. As the 120 hold of the vessel fills up the leg may be moved upwardly. The inclined movable chute may also be moved upwardly as the operator may see fit and this process can continue as the boat is filled until the leg and 125 the chute have both been raised as high as possible the only limit being the inclination at which the coal will flow freely through the movable chute since the end of the chute may be raised or lowered to compensate for 130

changes in level and give an additional adjustment.

After the vessel has been filled, then the parts can be raised a little higher so as to 5 clear the substructure and the boat can be drawn away without difficulty.

Thus there is at all times a continuous complete column of material extending from the loading point way up on the dock structure 10 through the different associated parts of the system down to the ultimate discharge point of the hold of the boat. There is no chance for any particle to fall causing undue comminution or reduction of the size of the materials handled or to cause any undue strain 15 on the material handling apparatus or any strain on the boat itself.

I claim:

1. A conveyer comprising a group of descending buckets, and inclosing case in which 20 said buckets travel provided with a longitudinal aperture along the line of travel of such buckets, a supply device adjacent the line of travel of such buckets, means whereby 25 the whole group of buckets and the supply device may have relative bodily movement one with reference to the other and means whereby the supply device at each position of such relative movement will deliver 30 through the aperture a definite quantity of material to each bucket as it passes.

2. A conveyer comprising a group of descending buckets and inclosing case in which 35 said buckets travel provided with a longi-

tudinal aperture along the line of travel of 35 such buckets, a supply device containing an intermittently acting delivery gate adjacent the line of travel of such buckets, means whereby the whole group of buckets and the supply device may have relative bodily 40 movement one with reference to the other and means whereby the supply device at each position of such relative movement will deliver through the aperture a definite quantity of material to each bucket as it passes. 45

3. In a conveyer the combination of a longitudinally apertured casing and a chain of buckets therein with a carriage slidably mounted on the casing adjacent the aperture, and feeding means mounted to shift with the 50 carriage means for delivering material from said feeding means through the carriage to the bucket chain and means on the carriage whereby at any position of the carriage it will deliver through the aperture a definite 55 quantity to each bucket as it passes said means comprising a controlling gate a driven link and timing wheel to operate said gate and a driving belt connection between the timing wheel and the bucket carrying belt. 60

In testimony whereof, I affix my signature in the presence of two witnesses this 24th day of April, 1917.

JOSEPH A. MACLENNAN.
